UNITED STATES PATENT OFFICE.

GEORGE A. DICKER, OF LANSINGBURG, NEW YORK.

DESIGN FOR A SASH-PULLEY CASE.

SPECIFICATION forming part of Design No. 30,055, dated January 24, 1899.

Application filed December 24, 1898. Serial No. 700,287. Term of patent 14 years.

To all whom it may concern:

Be it known that I, GEORGE A. DICKER, a citizen of the United States, residing at the village of Lansingburg, county of Rensselaer, 5 and State of New York, have invented and produced a new and original Design for a Sash-Pulley Case, of which the following is a full description, reference being had to the accompanying drawings, wherein—

10 Figure 1 is a front view of a sash-pulley case embodying my new design. Fig. 2 is a top plan view of the same, and Fig. 3 is a side view of the same.

The design consists in the ornamental 15 configuration of the case, which has the general form of a quatrefoil when viewed from the front, as shown in Fig. 1.

The case comprises the face-plates A A', 20 housings A² A³, and the bridges A⁴ A⁵. The bridges extend from one housing to the other

in rear of the face-plates, leaving the front portions of the housings, as well as the face-plates, separated from each other by the middle vertical face groove or slot B. The face-plates are provided with the parallel slotted 25 openings B' B² on opposite sides of the middle slot B.

The leading feature of the design consists in the quatrefoil form of the case when viewed from the front.

What I claim as new, and desire to secure by Letters Patent, is—

The design for a sash-pulley case herein shown and described.

In testimony whereof I have hereunto set 35 my hand this 22d day of December, 1898.

GEORGE A. DICKER.
